UNITED STATES PATENT OFFICE

2,555,085

TWO-LIQUID FEEDING REFLECTING DEVICE FOR COMBUSTION CHAMBERS IN PROPULSION APPARATUS

Robert H. Goddard, deceased, late of Annapolis, Md., by Esther C. Goddard, executrix, Worcester, Mass., assignor of one-half to The Daniel and Florence Guggenheim Foundation, New York, N. Y., a corporation of New York

Application May 15, 1948, Serial No. 27,283

4 Claims. (Cl. 60—44)

1

This invention relates to combustion chambers, as used in rockets and in other propulsion apparatus, in which two different combustion liquids are used.

It is the general object of this invention to provide improved means for feeding two different combustion liquids to a combustion chamber and for effecting intimate intermingling thereof.

A further object is to provide feeding means in which the intermingled liquids are thereafter reflected to a common focal point. In a modified construction, the intermingled liquids are successively reflected to a series of such focal points.

The invention further relates to arrangements and combinations of parts which will be herein-after described and more particularly pointed out in the appended claims.

Preferred forms of the invention are shown in the drawing, in which

Fig. 1 is a sectional elevation of one form of the improved feeding means;

Fig. 2 is a force diagram relating to the structure shown in Fig. 1; and

Fig. 3 is a sectional elevation of a modified construction.

Referring to Fig. 1, the improved feeding means is shown as mounted axially at the inner or closed end of a combustion chamber C of the usual form, as shown for instance in prior Goddard Patent No. 2,397,657 issued April 2, 1946.

The feeding means comprises an inner pipe 10 constituting a supply pipe for liquid fuel, as gasoline, and concentric tubular members 12 and 14 mounted in spaced relation to provide an annular passage P for an oxidizing liquid, such as liquid oxygen.

The outer tubular member 14 may be welded or otherwise secured in the wall of the chamber C, and vanes or partitions 16 and 17 hold the pipe 10 and tubular members 12 and 14 in fixed concentric spaced relation. It will be understood that the gasoline and liquid oxygen are both supplied under substantial pressure.

The pipe 10 and the inner tubular member 12 are separated by an annular space S which prevents freezing of the gasoline by the liquid oxygen before it enters the chamber C.

At its inner end, the inner tubular member 12 is outwardly expanded at 20 to provide an annular slot 21 between the expanded part 20 and the outer tubular member 14. Through this slot a sheet of liquid oxygen is injected into the combustion chamber.

The outer end of the pipe 10 is similarly expanded at 24, and a cap 25 is provided which

2

coacts with the expanded portion 24 to provide a second annular feed slot 27 for a sheet of liquid fuel or gasoline. The cap 25 is supported on a spider 28 mounted in the inner end of the pipe

5 10.

The annular sheets of gasoline and liquid oxygen cross and intermingle approximately at the point K. Very complete and satisfactory intermingling of the combustion liquids is thus effected.

A reflecting ring 30 is supported on arms 31 mounted on the outer tubular member 14, and the ring 30 is positioned for engagement by the intermingled liquids, as shown by the force diagram 15 in Fig. 2. The direction and mass of the gasoline is indicated by the arrow a, and the direction and mass of the liquid oxygen is indicated by the arrow b. The resultant direction of travel of the mixed liquids is indicated by the arrow c. The 20 mixed liquids thus engage the reflecting ring 30 and are reflected to a focal point F, at which the most intense combustion takes place.

A modified construction is shown in Fig. 3, in which gasoline is injected under pressure through 25 a pipe 40. An annular slot 41 is formed between the expanded end 42 of the pipe 40 and a cap 44 mounted on a spider 45. Liquid oxygen is supplied under pressure through an annular passage P' between an outer tubular member 50 and an 30 inner tubular member 52. The member 50 is welded or otherwise firmly secured in the inner end wall of a combustion chamber C', and the parts 40, 52 and 50 are held in spaced concentric relation by partitions 54 and 55.

The inner end of the outer tubular member 50 is expanded in bell shape, as indicated at 60, and is then reversely displaced and shaped to provide successive annular reflecting surfaces 61, 62 and 63 joined to the bell-shaped portion 60 by an 40 annular curved portion 65. At the inner end of the reflecting portion 61, a tubular member 66 projects inward and is expanded at 67 to provide an annular feeding slot 70 adjacent the slot 41 previously described.

45 The inner tubular member 52 is expanded at its inner end, as indicated at 72. The partitions 55 are extended to the end of the portion 72 to maintain the parts 61—72 in spaced relation.

The operation of the modified construction is 50 as follows: Liquid fuel, as gasoline, is supplied under pressure through the pipe 40 and is delivered as a flat sheet through the annular slot 41. Liquid oxygen is supplied under pressure to the passage P' and then travels through a passage P' 55 between the bell-shaped parts 60 and 72.

The liquid oxygen then travels reversely through the passage P3 between the bell-shaped part 72 and the inner reflecting portions 61 to 63.

The liquid oxygen is then delivered in sheet form through the passage P4 and the annular slot 70 and intermingles with the sheet of gasoline injected through the adjacent slot 41.

The intermingled liquids are then reflected by the surface 61 to a focal point F1, and such portion of the liquids as remains unvaporized passes through the focus and engages the reflecting surface 62 by which it is reflected to a second focal point F2. Any portion of the liquids which still remain unvaporized then engages the reflecting surface 63 and is reflected to a third focal point F3.

Three successive reflections are commonly sufficient to insure complete vaporization and complete combustion, but it will be understood that the series of reflections and focal points may be further extended, if found desirable under special circumstances.

Having described two forms of the invention and the advantages thereof, it will be understood that the invention is not to be limited to the details herein disclosed, otherwise than as set forth in the claims, but what is claimed is:

1. In a combustion chamber, an annular member having an inner reflecting surface, and axial means to project adjacent portions of two different combustion liquids substantially radially outward against said annular reflecting surface, and said reflecting surface being positioned at an outward obtuse angle to the axis so that liquids projected against said surface are reflected by said surface to a common axial focal point spaced axially from the entrance point of said liquids to said combustion chamber and toward the discharge end of said chamber.

2. In a combustion chamber, an annular mem-

ber having an inner reflecting surface, and axial means to project adjacent portions of two different combustion liquids substantially radially outward against said annular reflecting surface, and said inner reflecting surface being concave and positioned generally at an outward obtuse angle, so that liquids projected against said surface are reflected by said surface to a common axial focal point spaced axially from the entrance point of said liquids to said combustion chamber and toward the discharge end of said chamber.

3. In a combustion chamber, axial means to feed concentric conical sheets of two different liquids to a combustion chamber, and said chamber having an axially extended series of annular reflecting surfaces associated with said feeding means and by which intermingled portions of said two liquids are reflected to successive and axially spaced focal combustion points.

4. The combination in a combustion chamber as set forth in claim 3, in which each annular reflecting surface is frusto-conical and in which the successive reflecting surfaces are of successively increased diameter.

ESTHER. C. GODDARD,
*Executrix of the Last Will and Testament of
Robert H. Goddard, Deceased.*
